UNITED STATES PATENT OFFICE.

HENRY W. BENNER, OF CHAMBERSBURG, PENNSYLVANIA.

WATER AND COAL GAS MANUFACTURING APPARATUS.

No. 918,727.

Specification of Letters Patent.

Patented April 20, 1909.

Application filed September 24, 1908. Serial No. 454,495.

To all whom it may concern:

Be it known that I, HENRY W. BENNER, a citizen of the United States, residing at Chambersburg, in the county of Franklin 5 and State of Pennsylvania, have invented a new and useful Water and Coal Gas Manufacturing Apparatus, of which the following is a specification.

This invention relates to gas making apparatus, and has for its principal object to provide a novel form of apparatus for the economical production of both water gas and coal gas.

A further object of the invention is to provide an apparatus in which a portion of the heat ordinarily wasted in the process of heating up the superheater is utilized in the distillation of coal and the production of coal gas.

20 A still further object of the invention is to provide an apparatus combining means for the production of both water and coal gas, the parts being so arranged that the coke resulting from the distillation of the coal 25 may be utilized in the producer in the manufacture of the water gas.

With these and other objects in view, as will more fully hereinafter appear, the invention consists in certain novel features of construction and arrangement of parts, herein-after fully described, illustrated in the accompanying drawings, and particularly pointed out in the appended claims, it being understood that various changes in the form, 35 proportions, size and minor details of the structure may be made without departing from the spirit or sacrificing any of the advantages of the invention.

In the accompanying drawings:—Figure 1 40 is a sectional elevation of a gas plant constructed and arranged in accordance with the invention. Fig. 2 is a plan view of the same, partly in section, on the line 2—2 of Fig. 1. Fig. 3 is a transverse sectional view 45 on the line 3—3 of Fig. 2.

Similar numerals of reference are employed to indicate corresponding parts throughout the several figures of the drawings.

50 The producer 10 is of well known construction comprising a preferably cylindrical iron shell lined with fire brick and provided with a suitable grating 11 which may be

formed of fire brick or of metal, and below the grate is an ash pit 12, provided with a door indicated at 12', Fig. 2, which door may be opened for the purpose of admitting air at the starting of the operation. At a point below the grate is an air blast pipe 13 through which air under pressure is forced 60 when running a heat. At the top of the producer is a steam pipe connection 14 through which steam is introduced after the mass of fuel on the grate has reached the required degree of incandescence. The operation of this portion of the apparatus is well known, the coke or other carbon on the grate being burned until it reaches an incandescent state, after which the draft is cut off and steam is forced through the pipe 14 70 downward through the mass of incandescence fuel, the steam being decomposed and forming a water gas consisting of free hydrogen, carbonic acid, and a percentage of carbonic acid.

75 At a point adjacent the producer 10 is a superheater 15 which may be of the ordinary construction, that is to say, having a lining of firebrick, and filled with checker-work fire brick which is heated to a very high temperature, and into which the water gas ordinarily passes and is converted into a fixed gas by contact with the highly heated checker-work. In the present instance, however, the products of combustion from the producer 80 are not sent directly to the superheater, but are utilized for the purpose of distilling coal 85 and the manufacture of a coal gas.

90 Arranged adjacent the producer and the superheater 15 is a casing 20 which may be of any desired size and shape, but in the present instance is shown as of generally rectangular form. This casing is provided with a lining of asbestos and fire brick 21, and within the casing are arranged one or more retorts 22 that are supplied with bituminous coal to be distilled. The retorts are arranged vertically and extend from top to bottom of the casing, said retorts being preferably of generally rectangular form in cross 95 section and gradually tapering from one end to the other, the largest end being at the bottom, so that the retorts will be self discharging. The lower end of each of the retorts is closed by a hinged or slidable door 23, which 100 may be readily moved to open position for

the purpose of allowing the coke to fall by gravity into the pit 24 and from thence it may be loaded into the producer while still hot.

5 At the upper end of each retort is a casing 24 at the top of which is a feed hopper 25, and at the bottom of the feed hopper is a suitable valve 26 which is in closed position during the process of distillation. This valve 10 may be opened for the purpose of allowing the coal to flow from the hopper into the retort. The casings 24 are connected to a pipe 26' which leads to a hydraulic main of any ordinary type, where the tar and other heavy 15 matter is deposited, while the coal gas may pass on to any of the ordinary purifying devices.

Surrounding the retort is a checker-work fire-brick 28 which terminates short of the top 20 of the chamber forming an open space that is placed in communication with the top of the producer 10 by a pipe 30, and in this pipe is arranged a valve 31 which is moved to an open position when running a heat, so that the products 25 of combustion from the mass of carbon in the producer may pass through the pipe 30 to the top of the chamber 20 where the gases are met by a current of air entering through the blast pipe 33, thus supplying the initial 30 oxygen necessary for the support of combustion. The products of combustion pass downward through the checker work 28 heating the checker work and the retorts to a very high temperature, so that the coal will 35 be distilled and the vapor will pass off through the casing 24 and pipe 26' to the hydraulic main.

Leading from the lower portion of the casing 20 to the bottom of the superheater 15 is 40 a pipe 35 having a controlling valve 36, and this valve is opened while running a heat, so that the products of combustion after leaving the casing 20 may enter the superheater for the purpose of raising the temperature of 45 the latter to an extent sufficient to fix the water gas. The products of combustion entering the lower portion of the superheater are met by a blast of air that enters through a pipe 37, and the process of combustion will 50 be practically completed in the superheater, the waste gases passing out through an opening 38 at the top of said superheater.

In carrying out the invention, carbon, preferably the coke discharged from the retorts 55 22, is placed in the producer 10 and the two valves 31 and 36 are opened, while air is forced through the several blast connections 13, 33 and 37. The products of combustion arising from the mass of carbon in the producer 60 will pass through the pipe 30 to the chamber 20 where it will be met by the air from the pipe 33. The products of combustion then pass down through the checker work 28 and around the retorts heating the latter to such an extent that the coal within 65

the retorts will be distilled and the gas will pass off to the hydraulic main, as previously described. After leaving the bottom of the casing 20 the products of combustion pass through the pipe 35 to the lower portion of 70 the superheater and thence upward through the checker work of the superheater and out through the final discharge 38, heating the superheater to an extent sufficient to fix the water gas which is subsequently produced in 75 the producer 10.

The lower portion of the producer is connected to the lower portion of the superheater by a pipe 40 having a valve 41 which is always closed when running a heat. 80

After running a heat, which usually occupies from five to eight minutes, the valves 31 and 36 are closed and the vent valve 43 in the pipe 35 is opened in order to allow any gas which may remain in the chamber 20 to escape. The supply of heat from the producer is thus cut off from the chamber 20, but the heat retained by the checker work will be sufficient to carry on the process of distillation during the short interval of time that 90 the valves 31 and 36 are closed. The valve 41 is now open after all of the air blast connections have been closed, and steam is introduced through the pipe 14 into the top of the producer and this steam is forced down 95 through the mass of incandescent fuel and is decomposed into its constituent elements the oxygen uniting with the carbon to form carbonic acid, and the free hydrogen carbonic acid and a small percentage of carbonic acid passing off as water gas through the pipe 40 to the bottom of the superheater. This gas passes up through the superheater and becomes fixed by contact with the highly heated checker work and while passing into 105 or through the superheater an additional quantity of carbon may be added to enrich the gas by injecting a small quantity of hydrocarbon under pressure through a pipe 51, or by the aid of the steam jet, so as to enrich the gas to an extent sufficient to allow it to be used for illuminating purposes, if desired. This gas passes out through the pipe 50 to the scrubbers and other purifying apparatus. After a short time the temperature of 110 the carbon in the producer is reduced to such an extent as to be no longer available in the formation of water gas, and the valve 41 is then closed, while the valves 31 and 36 are opened to run another heat. 115

It will be noted that the retorts are arranged adjacent the producer, so that the resultant coke while still in a heated condition may be readily transferred to the producer and there utilized in the manner described. 120

It is, of course, obvious that in some cases the superheater may be eliminated and the entire volume of producer gas utilized in heating the retort chamber for the produc- 125 130

tion of coal gas or a series of retort chambers may be arranged to be heated by the gas so produced.

What is claimed is:—

- 5 1. In combination, a gas producer, a retort for the distillation of carbonaceous material, said retort being distinct from the gas producer, a retort containing chamber also separate and distinct from the gas producer, 10 a superheater, and connections between the producer and retort chamber, between the producer and superheater, and between the retort chamber and the superheater.*
- 15 2. In combination, a gas producer, a retort for the distillation of carbonaceous material, a retort containing chamber, checker work fire brick arranged within the chamber and surrounding the retort, a superheater or fixing chamber, and valved connections be- 20 tween the producer and the retort containing chamber, between the retort containing chamber and the superheater, and between the producer and the superheater, whereby the products of combustion in running a heat 25 may be directed into the retort containing chamber and then cut off during the gas making operation and the passage of the water gas to the superheater.
- 30 3. In combination, a gas producer, a superheater, a coal-gas-retort containing chamber arranged between the producer and the superheater, and means for coupling the gas producer to the superheater either directly or through the retort chamber at will.
- 35 4. In combination, a gas producer, a coal-gas-retort containing chamber, a superheater, means for directing the products of combustion from the producer into the said chamber and from thence to the superheater, and

means for cutting off the connections from 40 the gas producer to the retort chamber and for then causing the water gas from the producer to flow directly into the superheater.

5. In combination, a gas producer, a coal-gas-retort containing chamber separate and 45 distinct from the gas producer, a superheater, air blast pipes leading into each of said members, and valved connections between the said members whereby the products of combustion may, at will, be caused 50 to pass from the producer into said chamber and from thence into the superheater, and whereby the water gas may, at will, be caused to pass directly from the producer to the superheater. 55

6. In apparatus of the class described, a gas producer, a vertically disposed retort tapering from top to bottom, a discharge valve at the bottom of the retort, a casing arranged at the top of the said retort, a gas 60 discharge pipe leading from the casing, a supply hopper connected to the casing, a valve controlling communication between the hopper and the casing, a chamber containing the retort, checker work fire brick 65 arranged within said chamber and surrounding the said retort, a connection between the gas producer, and the said chamber, a superheater, a connection between the chamber and the superheater, and a connection be- 70 tween the gas producer and the superheater.

In testimony that I claim the foregoing as my own, I have hereto affixed my signature in the presence of two witnesses.

HENRY W. BENNER.
